UNITED STATES PATENT OFFICE

2,445,966

ADJUSTABLE RING HOLDER FOR
SPINNING MACHINESLeroy S. Peachey, Kenosha, and Raymond P.
Knoll, Lake Geneva, Wis.

Application March 5, 1947, Serial No. 732,592

6 Claims. (Cl. 57—122)

1

The present invention relates to new and useful improvements in spinners for silk throwing and appertains particularly to a ring holder for a conventional machine of the combined doubling and spinning frame type.

An object of the invention is to provide a spinner that will double and spin and produce substantially perfect, tightly wound bobbins.

A further object of the invention is to provide a spinner with an improved ring rail assembly whereby each ring is individually adjustable, vertically as well as horizontally.

A still further object is to provide a spinner with an adjustable ring holder which will allow for variations in the vertical setting of the individual ring as closely as desired while the machine is running.

Another object is to provide an attachment for spinning machines of this character which is simple and practical in construction, efficient and reliable in operation, relatively inexpensive to manufacture, easy to install in operative position on the machine without necessitating any changes or alterations in the construction thereof, and which otherwise is well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a top plan view with parts shown in section.

Figure 2 is an enlarged sectional view taken on a line 2—2 of Figure 1.

Figure 3 is an enlarged sectional view taken on a line 3—3 of Figure 1.

Figure 4 is a fragmentary top plan view of the ring showing the attaching yoke for the horizontal adjustment thereof.

Figure 5 is a perspective view of one of the brackets for the vertical adjustment of the ring.

Referring now to the drawing in detail, wherein, for the purpose of illustration, we have disclosed a preferred embodiment of the invention, the numeral 5 designates the annular ring holder of a spinning machine and which includes an inner upstanding annular flange 6 and a plurality of upstanding shouldered lugs 7 at its outer edge on which the conventional ring 8 is supported and secured thereto in any suitable manner. The usual wire traveler 9 is arranged to travel on the upper edge of the flange 6 with the outer end of the traveler riding under the ring 8, the traveler

guiding the thread 10 on the bobbin 11 in the usual manner while the thread is wound on the bobbin.

A support 12 in the form of a bolt has its lower end 13 threaded downwardly through the usual guide rail 14 of the machine and secured thereto by a jamb nut 15, the support extending upwardly from the guide rail and is bent horizontally at its intermediate portion as shown at 16 and terminates in an upwardly extending threaded end 17 to offset the upper end 17 from the lower end 13 of the support.

A bracket 18 of strap metal includes a lower horizontal portion 19 positioned above the guide rail 14 and is provided with an opening 20 through which the lower end 13 of the support 12 is freely inserted.

The outer edge of the ring holder 5 is formed at diametrically opposite sides with an outwardly projecting yoke 21 in which the lower end 13 of the support 12 is received and is secured in position on the lower end 19 of the bracket 18 by a clamping plate 22 which is secured to the bracket by screws or the like 23.

The bracket 18 also includes an upstanding end 24 terminating in a horizontal yoke 25 at its upper end overlying the lower horizontal portion 19.

A shouldered nut 26 is threaded on the upper end 17 of the support 12 and is formed adjacent its lower end with an annular groove 27 in which the yoke 25 is received. A coil spring 28 is positioned between the upper shouldered portion of the nut 26 and the yoke 25.

In the operation of the device, the support 12 is secured in a stationary position to the guide rail 14, as shown in Figure 3 of the drawing, and with the upper end 17 of the support positioned outwardly at one side of the ring holder 5. The yoke 21 of the ring holder is clamped to the lower portion of the bracket 18 and the yoke 25 at the upper end of the bracket 18 is engaged with the nut 26 threaded on the upper end 17 of the support 12.

By threading the nut 26 vertically on the support 12, the bracket 18 will be vertically adjusted on the support, whereby to vertically adjust the ring holder 5 and ring 8. In this manner, the battery of ring holders and rings carried by the spinning machine may be individually adjusted vertically without interrupting the operation of the machine. Likewise by loosening the clamping plate 22, the ring holder 5 may be adjusted horizontally.

In view of the foregoing description taken in

conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claims.

Having thus described our invention, what we claim as new is:

1. A mounting for the ring holder of a spinning machine comprising a support carried by the machine at one side of the ring holder, a bracket vertically adjustable on the support, and horizontally adjustable means connecting the bracket to the ring holder.

2. A mounting for the ring holder of a spinning machine comprising a support carried by the machine at one side of the ring holder, and a bracket connected to the ring holder and vertically adjustable on the support, said bracket supporting the ring holder for horizontal adjustment of the ring holder.

3. A mounting for the ring holder of a spinning machine comprising a support carried by the machine at one side of the ring holder, a bracket slidably mounted vertically on the support, and means connecting a ring holder to the bracket.

4. A mounting for the ring holder of a spinning machine comprising a support carried by the machine at one side of the ring holder, a bracket slidably mounted vertically on the support, said bracket supporting a ring holder for horizontal adjustment thereon.

5. A mounting for the ring holder of a spinning machine and comprising a plurality of upstanding supports carried by the machine at opposite sides of a ring holder, a bracket vertically adjustable on the supports, and means carried by the holder and having a horizontally adjustable connection with the bracket.

6. A ring holder for spinning machines having a plurality of yokes projecting radially therefrom, upright supports carried by the machine and received in said yokes, a bracket slidably mounted on the supports, vertical adjusting means between the support and the bracket, and means connecting the yokes in horizontally adjusted position to the brackets.
